KARL MEY, OF BERLIN, GERMANY, ASSIGNOR TO GENERAL ELECTRIC COMPANY, A CORPORATION OF NEW YORK.

METHOD AND MACHINE FOR MANUFACTURING INCANDESCENT LAMPS AND SIMILAR ARTICLES.

Application filed October 5, 1925, Serial No. 60,585, and in Germany October 31, 1924.

In quantity manufacture of electric incandescent lamps, electron tubes, and similar sealed glass vessels with sealed-in inner parts, the transfer of the lamps or glass vessels from the sealing-in machine to the exhaust machine has so far always caused loss by breakage. This loss was due to mechanical injury by the handling necessary to make the transfer and also to the fact that the lamps, while still hot from the sealing-in machine, or only partly cooled off, were in the transfer usually exposed to cold air currents. Then the re-heating of the lamps when being exhausted often caused further loss by breakage. To reduce the breakage incurred between the sealing-in machine and the exhaust machine in the course of manufacture the two machines have been put close together in a so-called unit machine, and have also been mounted coaxially and one above the other, by coupling their rotary spiders. With this latter arrangement the interior parts or mounts were first sealed into the bulb on the upper spider and the lamp was then taken out by hand and placed on the lower spider where it was exhausted. A transfer is as necessary when the machines are placed one above the other as when they are placed side by side and although it is carried out more rapidly it still has all the disadvantages and inconveniences of transferring the sealed-in vessels.

This invention has for its object the entire elimination of the disadvantages and inconveniences of transferring the sealed-in vessels. To this end the mounts, each consisting of the stem and inner parts of the lamp, are continuously and in succession sealed into the bulbs on a single carriage, advantageously a rotary spider, which serves to convey the mounts and the bulbs, to the sealing-in position and then to convey the sealed-in vessels to a position where they are exhausted and also if desired filled with gas, all without being changed in position on the spider which is preferably actuated step by step. In addition to the decreased breakage and waste thus obtained there is a further decrease in the cost of manufacture, since the work of changing each lamp from the sealing-in machine to the exhaust machine is entirely eliminated.

The combined sealing-in and exhaust machine serving to carry out this process and replacing the sealing-in machines and exhaust machines hitherto used can be so built that the lamps to be finished pass along a straight path; it can also however be built to advantage, as already said; so that the lamps move along a circular path. As every lamp after passing through the various sealing-in and exhaust positions again returns to its original place, one attendant can set the lamp parts to be sealed together into the machine and remove from it the finished and exhausted lamps.

In the drawing there is shown, as one example of construction, a machine constructed in accordance with the invention and suitable for carrying out the new process.

Figs. 1 and 2 show the machine in diagrammatic illustration in vertical section and in top view;

Fig. 3 shows a vertical section through a head which holds the exhaust tube of a mount;

Figs. 4 and 5 show in elevation and plan the mechanism for actuating the devices for releasing and gripping the exhaust tubes set in the heads;

Figs. 6 and 7 show in elevation one of the bulb holding forks, and illustrate the raising and lowering of the bulb holding forks;

Figs. 8 and 9 show in elevation and in top view a rotary preheating and sealing-in burner;

Fig. 10 shows a vertical section through a valve which responds to leaky lamps and causes them to be sealed off automatically before they interfere with the operation of the vacuum pump; and

Fig. 11 shows on a larger scale the sealing off torch and discharge fork in the sealing-off position.

The machine, preferably made with a rotatable spider or turret, and advantageously rotated step by step, has, in the example shown, twenty-four working positions which are marked 1 to 24 in Fig. 2. In the positions 1 or 2 the mounts and bulbs are put in their respective holders; in position 3 the bulb is lowered into place over the mount; in positions 4 to 10 the sealing-in of the mounts, the drawing down of the seal, and

the bending up of the leading in wires occur; in positions 11 to 23 the exhaust and also, if desired, the filling of the lamps by gas is accomplished; and in position 24 the lamp is sealed off and lifted out of the machine.

The machine consists, as in the usual rotary exhaust machine, of a central stationary valve seat *a* and a rotatable spider having a flat rotary valve *b* fitted on the seat and fixed to a rotary shaft *c* which extends through the stationary valve seat. The rotary valve has ports *d* arranged in a circle and corresponding in number to the working positions of the machine, which in each revolution of the spider successively register with parts in the valve seat *a* connected to the various pipes leading into the stationary valve seat to establish connections through the valve with the atmosphere, the exhaust pumps, not shown, a compressed air reservoir, and also with a reservoir of inert gas for filling the lamps. At the ports *d* of the rotary valve *b* terminate radial tubes *f* which open at their outer ends into the exhaust heads *g* mounted on the rim of the spider and designed for holding the mounts to be fused into the bulbs. The mount is of a known type and as shown in Figures 3 and 7 consists of a filament mounted on a glass stem which is of the tipless type and is made up of a central rod or arbor *h* and an exhaust tube *h*¹ both secured to the inner end of a stem tube or flare *h*² which has its outer end flared into a flange, the exhaust tube *h*¹ being longer than and concentric with the stem tube, and projecting from it some distance, as shown in Figure 3. For every exhaust head *g* there is a bulb holding fork *i* for holding the bulb *k* in place over the mount. The separate holding forks *i* are fixed, either to the relatively rigid tubes *f* of the heads or to a special supporting ring which rotates with the rotary valve.

Each exhaust head *g* consists as shown in Fig. 3, of a tubular boss *g*¹ into whose central cylindrical bore, somewhat enlarged at the upper end, there is set a tubular rubber stopper *l* having conical upper and lower ends and fitted between two pressure rings *l*¹, *l*² advantageously made of metal and each having a conical recess which fits the adjoining end of the stopper *l*. The rubber stopper *l* and the cooperating metal rings *l*¹ and *l*² have coaxial central bores so as to receive the small exhaust tube *h*¹ on the stem *h*² of the mount *h*. Pivoted on the upper pressure ring *l*² of the rubber stopper on pivots *l*³ are centering jaws *l*⁴ for centering the exhaust tube *h*¹ and having inclined cheeks *l*⁵. The centering jaws are embraced by a tension ring *l*⁶ which has a tapered bore cooperating with the inclined cheeks of the centering jaws and which is slidably mounted in an outer sleeve *g*² of the head to be under the influence of a spiral spring *l*⁷ set into the head and tend-

ing to hold the ring against the upper end *g*³ of the sleeve *g*². In the interior of the sleeve *g*² two rods *m* are slidably mounted in grooves 180° apart on the head. The upper ends of these rods are connected by pins *m*¹ 70 with the pressure ring *l*² of the rubber stopper, whilst their lower ends are provided with pins *m*² which project into two inclined slots *m*³ in a cap *m*⁴ which is rotatively mounted on the lower end of the boss *g*¹ by a 75 set screw *m*⁵.

In the open position the parts of the head take the position shown in Fig. 3. The bore of the rubber stopper is then so large that the exhaust tube can be easily inserted and just 80 as easily again removed from the rubber stopper. If however, cap *m*⁴ is turned in such a direction that its inclined slots *m*³ pull down the pins *m*² and with them the rods *m* and the pressure ring *l*² the rubber stopper is 85 compressed between the stationary pressure ring *l*¹ and the movable pressure ring *l*² until the walls of the bore of the rubber stopper bear in their entire or almost entire length tightly against the exhaust tube *h*¹ of the 90 mount as a result of the conical end surfaces of the stopper cooperating with the correspondingly conical recesses in the rings *l*¹ and *l*², so that not only is the exhaust tube *h*¹ connected airtight to the tube *f* opening into the 95 head *g*, but at the same time the mount is held fast in its position. When the pressure ring *l*² is pulled down the clamping jaws *l*⁴ carried by it and also the tension ring *l*⁶ are simultaneously moved downward. The ten- 100 sion ring *l*⁶ follows this downward movement however only for a part of the way, as the spiral spring *l*⁷ with a progressive compression continually exerts a greater counterpressure. As soon as the tension ring *l*⁶ 105 no longer follows the downward movement of the clamping jaws *l*⁴ there occurs a relative displacement of the inclined cheeks of the clamping jaws and of the tension ring lying against one another which produces an 110 inward movement of the clamping jaws, whereby these bear, like the rubber stopper, tightly against the exhaust tube and center it in an exactly vertical position, so that no fear need be had that the mount may 115 be sealed crookedly into the bulbs. This feature is very important in the handling of the machine, as the attendant no longer has the responsibility, in the continuous sealing-in and exhausting, of supervising the 120 sealing-in and straightening out by hand any crookedly sealed-in mount while the seal is still soft.

The end of the exhaust tube still remaining in the rubber stopper after sealing off the 125 lamp is released by the opposite rotation of the cap *m*⁴, which by its reverse rotation raises the pull rods *m* together with the pressure ring *l*² and the clamping jaws *l*⁴. The tension ring *l*⁶ is likewise moved upwardly, 130

but only to its initial position, and the upward movement of the centering jaws l^4 through the ring displace the inclined cheeks of the centering jaws l^4 on the ring and again 5 allows them to assume the unclamped or open position.

The rotation of cap m^4 necessary for clamping and releasing the exhaust tube is advantageously produced in two successive working 10 positions of the spider, preferably in positions 1 and 2. In these working positions there are arranged vertically below the heads two rotatable and vertically movable keys n in two stationary bosses n^1 , which have 15 upwardly sloping but relatively displaced bayonet slots n^2 for controlling the guide pins n^3 on the keys. To the lower ends of the keys are fixed pinions n^4 , which are in constant engagement with the teeth of an offset double rack n^5 . The latter is at every 20 step of the rotation of the machine moved once to the left and right through a pivoted lever n^6 actuated by a cam disc n^7 controlled by the machine drive. The movement of the 25 rack n^5 rotates the pinions n^4 and the keys n solidly connected with them simultaneously but in opposite directions. The pins n^3 sliding in the bayonet slots n^2 raise or lower the keys n , depending on the direction of rotation 30 of the pinions n^4 , and also at the same time raise and lower the pinions n^4 , which are made somewhat broader than the rack n^5 in order that they may not become disengaged from the rack n^5 by the raising and lowering 35 of the keys and pinions which occurs simultaneously with their rotation. At the upper end of each key are two lugs n^8 , which, when the keys are in the high position, engage correspondingly arranged lugs m^6 of cap m^4 and carry them along in the direction of rotation 40 of the keys.

As soon as the spider has completed one step of its rotation, it remains in position for a certain period, about four to six seconds, 45 during which the rack n^5 will be moved to the left into the position shown in Figs. 4 and 5. During this movement of the rack the two keys are moved upwardly from the lower position shown in Fig. 3, and in consequence 50 of the arrangement of the bayonet slots n^2 are at the same time turned in opposite directions. The lugs n^8 on the keys engage the corresponding cap lugs m^6 and thereby turn the caps of the two adjacent 55 heads in opposite directions. Cap m^4 located to the left and on the exhaust head at working position 1 has, by its rotation, caused an upward movement of the rods m and thereby the release of the rubber stopper l and 60 of the centering jaws l^4 , so that in this working position 1 the end of the exhaust tube h^1 still remaining in the rubber stopper from the sealing-off is released and can be removed. Cap m^4 located to the right and 65 on the exhaust head at working position 2

has, on the contrary, by its rotation pulled down the rods m , and thereby automatically brought the rubber stopper l and the centering jaws l^4 into the clamping position, so that the new mount previously inserted by 70 the attendant has in this working position 2, its exhaust tube clamped fast simultaneously with the release of the sealed off exhaust tube in position 1. As the two heads still remain for a short time, about two seconds, in position after the rotation of their caps, the attendant can also each time, after the release and removal of the sealed off exhaust tube end, insert, at working position 1, a new mount into the open rubber stopper, 75 which then, when the head reaches the working position 2, is clamped fast automatically in the working position 2 during the release of the next following sealed off exhaust tube end. Whilst the heads still remain in the 80 two working positions 1 and 2 shown, the rack moves, as shown by the arrows, into the right hand position. The pinions n^4 and keys n are thereby likewise moved in the 85 opposite direction whereby the key lugs n^8 80 are moved away from the lugs of the caps m^4 which remain in position. The parts of the head at working position 2 and shown to the right in Fig. 4 thus are left in the closed position and remain so during the 90 further travel of the spider until this head completes one revolution and again reaches the position shown to the left in Figure 4, that is, the working position 1, where the release of the sealed off exhaust tube end occurs simultaneously with the closing of the preceding head which is in working position 95 2.

The keys n acting on the heads need not necessarily be placed in two adjacent working 100 positions of the machine. The key which effects the clamping in of the newly inserted mount may, for example, be placed in working position 3 or 4.

Each bulb holder consists of a bulb holding fork i fixed to the upper end of a vertically movable rod i^1 . Each rod i^1 is slidably mounted in a fixed guide i^2 which travels with the machine and is, during the time in which the heads and the holding 110 forks travel through the sealing-in and exhaust positions, held in its lower position by a flat stop spring i^3 fixed to the guide i^2 to enter an upper holding notch in the rod i^1 in which position the bulb k set in the holding 115 fork, encloses the mount h . Shortly before or during the introduction of the bulbs into the holding forks the rods i^1 are automatically raised so that the introduction of the 120 bulbs can cause no damage to the mounts h set simultaneously or shortly before in the rubber stoppers l . For this purpose there is arranged at either working position 1 or 2 in a stationary part o of the machine a vertically movable lifter o^1 over which the rod 125

i¹ of the holding fork *i* comes when it reaches that working position. Whilst the rod remains in this working position, the lifter *o¹* is moved once up and down by the 5 drive of the machine by, for example, a cam disc. When the rod reaches the working position in which it registers with the lifter the latter assumes the low position shown in Fig. 6, and then, while the carrier of the machine is stationary, moves upwardly, thereby 10 pushing up the rod *i¹* and pressing aside the stop spring *i³* out of the holding notch. At the end of the upward movement the pawl-like stop spring *i³* snaps into a second lower 15 holding notch of rod *i¹* and thus locks it, together with the holding fork, in the high position. As soon as this has been accomplished the attendant can introduce bulb *k*, without damaging mount *h* introduced into 20 the underlying rubber stopper simultaneously or somewhat earlier or later.

In the working position 3, in which the holding fork moves into the low position, there is likewise supported on a stationary 25 bracket *p*, which may also be in one piece with the frame part *o*, a vertically displaceable pull rod *p¹* which carries at its upper end a spring controlled pawl *p²*. This pull rod is also actuated once by the drive of the 30 machine at every stoppage of the spider, and is advantageously first pulled down and then pushed up. In the downward movement the pawl *p²* engaging with a notch *i⁴* of the rod *i¹* carries along the rod by forcing back the 35 pawl like spring *i³*, until at the end of the downward movement the pawl like spring *i³* again snaps into the upper notch of rod *i¹* and thereby secures the rod, together with the holding fork, in the low position. The 40 bulb *k* set into the holding fork is thus automatically placed over the mount *h*. While the holding fork still remains in this working position, or as soon as a new holding fork reaches this working position, the pull 45 rod *p¹* moves upward, during which the pawl *p²* moves out of the way and thus does not influence rod *i¹*.

In the sealing-in positions 4 to 8 the superposed bulb is sealed to the mount *h* clamped 50 fast in the head *g* by the rotating preliminary heating and sealing in burners. Each burner consists of a rotatable fork *q*, Fig. 8, embracing the bulb from the top and consisting 55 of parallel tubes having, at their lower-ends, burner nozzles *q¹*. The central feed tube *q²* placed axially of the bulb acts as the axle for the rotating tube fork and for this purpose it is rotatively supported in two stationary 60 bearings *q³* and *q⁴*. Between these two bearings there is mounted on each tube *q²* a pinion *r*. The pinions *r* of all tube forks are connected to one another by intermediate gears *r¹* and are all rotated in the same direction by a driving gear *r²* engaging with one 65 of these intermediate gears. In order that

the tube forks may not interfere with one another in this rotation they are advantageously, as shown in Fig. 2, angularly displaced relative to one another. The gears *r¹, r²* rotated by the machine drive are always 70 automatically stopped when the spider is making a partial rotation to move the holding devices with the mounts and bulbs from one position to the next, and stop in such a position that the bulbs pass unhindered through 75 the tube forks and do not strike against one or the other tube forks. The gears are stopped by a locking gear, which acts on the vertical shaft *r³* of gear *r²*. The locking gear consists of a locking wheel *s* keyed on shaft *r⁴*, a 80 spring influenced locking pawl *s¹* and an actuating pawl *s²*. The latter carries a roller *s³*, which runs on a cam disc *s⁴* kept in continuous rotation by the machine drive. During the stoppage of the spider this roller *s³* 85 runs on the raised cam part of disc *s⁴*, with the result that the actuating pawl *s²* takes the position shown in dotted lines and the locking pawl *s¹* is also pressed into the dotted line position against the action of spring *s⁵*. The 90 locking wheel *s* is thereby released and during the stoppage of the machine renders possible a rotation of shaft *r³* of the toothed wheels *r, r¹, r²* and of the tube forks *q* together with the burners *q¹*. As soon as the 95 spider makes a partial rotation, the roller runs off the raised cam part, and the spring *s⁵* comes into action and presses the pawls *s¹, s²* into the positions shown in full lines. the locking pawl *s¹* then prevents a further 100 rotation of the gears and holds the tube forks fast in a definite position which allows free passage to the bulbs.

The upper ends of the rotatable burner feed tubes *q²* open into fixedly supported 105 stuffing boxes *q⁵*, into which gas is continually fed from a common source of supply. In place of the stuffing boxes there could also be used rotatably supported valves regulating the feed of the gas. In order to be able to 110 regulate the burner action, the tube forks *q* are advantageously arranged so that they can be adjusted in height. For this purpose there is screwed into the upper stationary framebox *q⁶* of every fork a sleeve *q⁷* which 115 receives the tube *q²* and on the upper flange rim *q⁸* of which there rests a connection *q⁹* of tube *q²* with the interposition of a ball bearing *q¹⁰*. As soon as sleeve *q⁷* is turned to the left or right, there is produced either a raising or a lowering of the tube fork *q*. In order that the gear *r* placed on tube *q²* may remain in position, a pin and slot connection 120 is provided between it and the tube. The adjustment in height of the burner flames 125 can also be produced by arranging the burner nozzles to be adjustable. Such adjustable burner nozzles can also be used with tube forks adjustable in height, in which case then a rough adjustment of the burner flames 130

becomes possible by adjustment of the tube-forks and a fine adjustment of the same by the movement of the burner nozzles.

In order that, during the sealing-in process, the part of the exhaust tube located directly under the stem h^2 of the mount and the leading-in wires t depending along the exhaust tube h^1 may not be damaged by the burner flames, the outer sleeves g^2 of every head is, shortly before the introduction of every bulb into the first sealing-in position 4, raised so far that the narrower neck part g^4 of the sleeve connecting with the end g^3 embraces the exhaust tube h^1 with the leading in wires t and that the flange g^5 of the sleeve comes to bear on the stem h^2 of the mount. The flange of the outer sleeve g^2 then forms during the sealing-in process a support for the stem of the mount so that the mount cannot be fused into the bulb in a slanting position. The raising of the outer sleeve g^2 is effected by means of a roller g^6 arranged on the lower rim of the sleeve and which, before the head, together with the mount and bulb reaches working position 4, runs onto a stationary cam g^7 of the machine. It is advantageous to so form the upper surface of the curved cam g^7 that sleeve g^2 is at first only partly raised and is completely raised only shortly before coming into the second sealing-in position 5. Before the head leaves the last sealing-in position 8, the separation of the superfluous bulb neck is effected close below the stem h^2 at the sealing zone. The separated bulb neck h^1 drops down and remains suspended on the outer sleeve g^2 as shown in dotted lines in Fig. 3. Shortly after the last sealing-in position 8 the roller g^6 again runs off the stationary cam g^7 , causing an automatic lowering of the outer sleeve g^2 with a release of the protected exhaust tube. Before the head with the now sealed-in mount reaches working position 9 the superfluous bulb neck h^1 hanging to the outer sleeve is automatically destroyed by two stationary cheeks u forming a narrow passage through which the upper part of the head passes in its travel from working position 8 to working position 9.

In the working position 9 the two segment-like burners v are mounted to further heat the sealing-in zone of the bulb neck still hot from the sealing-in process, so that the seal formed at the stem h^2 can be pulled down or somewhat stretched in this working position. This is done by a slight raising of the bulb holding fork by means of a lifter not shown, but similar to the lifter o^1 at position 2 which as soon as the lamp has stopped for a few moments in working position 9 is raised very slightly by the drive of the machine similarly to lifter o^1 . As however in this slight raising of the bulb holding fork with the sealed in bulb in it the mount is held fast by the grip on the exhaust tube h^1 of the compressed

rubber stopper and the centering jaws, the outer edge of the hot softened flange of the stem tube is slightly bent upwards and thereby the seal is drawn down somewhat with an equalization of the glass and removal of strains in it.

In the next working position the outer lead wires t secured to the inner end of the stem tube and extending down along the exhaust tube are automatically raised into a horizontal position, so that later on these wires are not in the way when the exhaust tube is closed by fusion in the sealing-off positions and are not fused off. For this purpose there are in the path of movement of the lamp a lead wire bender comprising two double hooks w set to be tangential to the exhaust tube h^1 of a mount in a head g and displaced relative to each other. These hooks may be mounted on stationary supports w^1 so as to swing toward and away from each other and thus supports w^1 can, as shown, be placed on the segment-like heating oven x extending over the exhaust positions 11 to 23, or in any other desired manner. The exhaust tube of the lamp coming into working position 10 presses these double hooks w somewhat apart, whereupon the lead wires t depending from the stem tube and lying alongside the exhaust tube are caught in the forward bends w^2 of the double hooks. When the lamp moves further into the next working position 11, the lead wires t which are held fast in these forward bends w^2 are bent up as the wires move out of these bends and are bent high into a horizontal position and kept there by the bends. In order to insure the bending up of the lead wires the hooks have rear bends w^3 , which hold any lead wires not caught by the forward bends w^2 and then cause these wires to be bent up in the further travel of the lamps. In the working position 11 the lamps still hot from the sealing in operation enter the segmentlike heating oven x , which keeps the lamps hot during the exhaust for the purpose of a careful evacuation and the expulsion of all residual gas and water vapor. The lamps thus never cool to a dangerous extent in their entire passage through the machine. In the different working positions 11 to 23, every lamp is, in the manner known in rotatable exhaust apparatus, connected several times to a pre-vacuum pump and to several fine pumps and automatically connected if desired to gas filling receptacles.

Should a lamp have become damaged, perhaps by a defect in the sealing-in process, it is automatically sealed off in the first pump position 11 closely below the stem h^2 . This automatic sealing off of the defective lamp is controlled by a valve y , which is placed at working position 11 at the entrance to the oven and is in communication with that conduit of the stationary valve seat a which leads to the rough or pre-vacuum pump. This con-

trol valve y , which is responsive to a leaky lamp consists, as seen in Fig. 10, of a closed casing, containing two flexible diaphragms or membranes y^1 , y^2 mounted on opposite sides 5 of a partition y^3 in the casing. The two membranes form the outside walls of two chambers y^4 , y^5 separated from each other by the partition y^3 and are in communication with one another through a port in the partition 10 controlled by a valve y^6 on a stem y^7 which extends through the intermediate partition y^3 . The valve y^6 ordinarily shuts off the chambers y^4 , y^5 from each other, so that the combustion gas or combustion mixture fed 15 to chamber y^4 by conduit y^8 cannot flow into chamber y^5 and from this through conduit y^9 to a sealing off burner y^{10} mounted in the heating oven in position to fuse the exhaust tube of a passing lamp. The lowermost 20 chamber y^{11} of the control valve is formed by the casing and the lower membrane y^2 and is connected by conduit y^{12} with the prevacuum pump, and by conduit y^{13} through the rotary valve a , b of the machine, with the interior of 25 the lamp which is in the working position 11. The uppermost valve chamber y^{14} is formed by the casing and the upper membrane y^1 and is connected with a constant vacuum which may be one of the fine vacuum pumps, by the tube 30 conduit y^{15} . In the uppermost chamber there may be further provided to advantage a spring y^{16} , which by pressure on the uppermost membrane y^1 presses the valve disc y^6 tightly to its seat. If the lamp which reaches 35 working position 11 is perfect, the pressure in chamber y^{11} and that in chamber y^{14} are so nearly the same that the valve disc y^6 is kept tightly on its seat by the action of spring y^{16} . As soon however as a leaky lamp reaches this 40 working position, air will leak into the lowest chamber y^{11} thereby disturbing the position of equilibrium of both membranes y^1 , y^2 since the fine vacuum pump maintains in the uppermost chamber y^{14} a pressure so much 45 lower than that in the lower chamber y^1 into which the air is leaking that the upper membrane y^1 is lifted, thereby raising the valve disc y^6 and overcoming the spring y^{16} . Connection between the two central chambers y^4 , y^5 is established by the lifting of the valve 50 disc y^6 , and the combustion gas thereby passes at once through the opening of the partition y^3 to the sealing off burner y^{10} , which then forms a blowpipe flame, which melts off close 55 to the stem tube or flare h^2 the exhaust tube h^1 of the lamp at working position 11.

This automatic sealing off of leaky lamps is very important for the operation of the combined sealing-in and exhaust machine, as 60 the operator is not in a position, on account of the size of the machine and the sealing-in and exhaust being effected successively without any interruption, to recognize leaky lamps quickly and remove them by hand. If 65 a leaky lamp is not automatically sealed off,

but goes through the other pump positions of the machine, several of the lamps following the leaky lamp would not be sufficiently exhausted, as the leaky lamp permits a passage of air into the different pumps and thus 70 dangerously decreases their working capacity.

In order that the rubber stoppers inserted in the heads may not be damaged by the heat of the heating oven x while the lamps are on the pumps, the different outer sleeves g^2 of 75 the heads have, cooling jackets g^8 which are continually traversed by a cooling liquid, for example water. The cooling liquid is advantageously fed through each cooling jacket g^8 , as shown in Fig. 1, by a supply or distributing 80 tube g^9 and a discharge conduit g^{10} which delivers the cooling liquid to a collecting trough g^{11} from which it escapes through a conduit 85 g^{12} .

After traversing the heating oven x the 85 lamps provided with the sealed-in mounts and exhausted and mayhap also filled with gas, reach the sealing-off and delivery position 24 at which there is a delivery fork z radially movable and likewise actuated by 90 the machine drive. In its forward movement the fork z passes just below the stem of the lamp and catches the exhaust tube between the prongs of the fork. To the delivery fork z there are fixed two sealing-off burners 95 z^1 , advantageously displaced relative to each other by 180° , which, as soon as the delivery fork has been pushed forward, seal off the exhaust tube close to the stem. The lamp resting on the delivery fork but still dependent from the bulb holding fork i can then be conveniently lifted out by the operator and deposited in a collecting container. By means of the delivery fork z , the sealed-off and detached lamp can also be automatically 100 lifted from the bulb holding fork i and be automatically deposited. To obtain this result it is only necessary to tip up the lifting-off fork in its forward position and then to so turn or swing it about after or during the 110 withdrawal, that the lamp resting on the delivery fork automatically drops into a conveyor-duct arranged beside the delivery fork.

In order to prevent with the greatest certainty any damage to the leading in wires t 115 when sealing off the lamp, the delivery fork z radially movable to the machine is provided with a spring catch which catches and turns up any dependent lead wire during the forward movement of the delivery fork. The 120 catch may consist for example, as shown, of a single arm lever z^2 which is ordinarily held by a spring z^3 against a stationary stop z^4 and which carries at the forward end a hook shaped spring z^5 . In the forward movement 125 of the fork z the bend of the spring z^5 strikes against the exhaust tube h^1 and slides about the exhaust tube by swinging out the lever z^2 . Any lead wire which may be still depending from the stem tube and lying alongside 130

the exhaust tube is then caught by the bend of the hook spring z^5 and bent up horizontally in the further forward movement of the fork z into its forward position shown in dotted lines in Figure 11.

In the sealing-off position 24 of the machine the lamp, after the sealing-off is completed, is advantageously subjected in the known manner to a test as to its good vacuum, by bringing the lead wires into connection with a source of current.

In the further rotation of the spider the head g still carrying the stub end of the sealed-off exhaust tube again comes into working position 1. In this working position tube f leading to the head is connected by the rotary valve b of the machine with a compressed air reservoir connected to a port in a valve seat a , so that compressed air passes into the interior of the head which is at position 1 and holds the stub end of the exhaust tube fused shut at its upper end. The compressed air tends to blow out the stub end of the exhaust tube, but cannot do so as long as the exhaust tube end is clamped fast in the rubber stopper 1 and the centering jaws l^4 .

After a few moments halt of the head in working position 1 the automatic release of the rubber stopper and the centering jaws l^4 is effected, as previously described, by the rotatable key n and the upwardly actuated pull rod m , and the compressed air becomes effective to force the released stub end of the exhaust tube out of the head g . There can now be repeated the introduction of a mount and of a bulb either in working position 1 or 2 and the subsequent operation o in the other working positions of the machine.

Due to the large number of working positions and to the fact that the machine need stop for only a few seconds in each working position, a large number of lamps, six hundred and more can be continuously produced by the machine in an hour.

The number of working positions on the machine may be smaller or larger, according to requirement. The sealing-off of the lamp can be done in two working positions instead of in one working position, and that in such manner, that in the first sealing-off position the exhaust tube is merely fused shut, and then is entirely melted through in the second working position. The fastening of the exhaust tube in the rubber stopper and the mode of movement of the sealing-in burners can also be done in various ways. Then too the means for bending over the leading in wires and for the sealing-off of the lamps may be of other constructions.

What I claim as new and desire to secure by Letters Patent of the United States, is:

1. The method of manufacturing incandescent lamps and similar articles comprising a bulb and a mount having an exhaust tube, which consists in holding the mount and

carrying it bodily along a predetermined path by means of said exhaust tube, placing the bulb over the mount at a predetermined point of said path and thereafter maintaining substantially unchanged the relative position of said mount and said bulb during the remainder of the travel of said mount, sealing said mount into said bulb at another point of its path, thereafter holding said sealed vessel by said exhaust tube, exhausting the sealed vessel through said exhaust tube at still another point of its path, and sealing off said vessel.

2. The method of manufacturing a hermetically sealed evacuated device comprising a glass vessel formed by sealing together two glass parts, one tubulated with an exhaust tube, and then exhausting the vessel, which consists in holding the tubulated part in predetermined position by said exhaust tube only, and continuing to hold the tubulated part in said position by the exhaust tube while the other part is brought into sealing in relation to it and said tubulated part is sealed into said other part and then exhausting the sealed vessel so formed through said tubulated part while it is positioned by said exhaust tube.

3. The method of manufacturing an incandescent lamp by sealing together a bulb and a mount, one tubulated with an exhaust tube, and exhausting through the tubulated part, which consists in holding the tubulated part in position solely by said exhaust tube throughout the sealing in and exhaust of said lamp, bringing the untubulated part into sealing in relation to said tubulated part while it is so held and sealing said parts together to form said lamp, and exhausting the sealed in lamp through said exhaust tube while so held.

4. The method of manufacturing incandescent lamps and similar articles comprising a bulb hermetically sealed to a mount having an exhaust tube, which consists in holding the mount by said exhaust tube with said exhaust tube in air tight connection to an exhaust conduit, placing the bulb over the mount while so held by the exhaust tube, hermetically sealing said mount into said bulb while said mount is so held and thereby forming a sealed vessel, and connecting said exhaust conduit to an exhaust pump and exhausting the sealed vessel through said exhaust tube while still so held.

5. In a machine of the character described, an exhaust head comprising a tubular boss, a tubular rubber stopper in said boss for receiving an exhaust tube, and centering jaws concentric with the bore of said stopper and movable radially thereof to grip an exhaust tube and center it in said stopper.

6. In a machine of the character described, an exhaust head comprising a tubular boss, a tubular rubber stopper in said boss having conical ends, a compression ring at each end

- of said stopper and each ring having a conical recess to cooperate with the conical end of said stopper and said rings being movable toward each other longitudinally of said stopper to compress said stopper and constrict its bore.
7. In a machine of the character described, an exhaust head comprising a tubular rubber stopper having a conical end, a ring having a conical recess engaging said end of said stopper, and movable toward the other end of said stopper to compress said stopper and its bore, and centering jaws pivoted on said ring to be movable radially of the bore of said stopper to center an exhaust tube in said stopper.
8. In a machine of the character described, an exhaust head comprising a tubular boss, a tubular rubber stopper in said boss, centering jaws mounted in said boss to move radially of the bore of said stopper and having cheeks inclined to the bore of said stopper, and a tension ring concentric with said stopper and movable longitudinally thereof and having inclined surfaces to engage with the inclined cheeks of said centering jaws to close them, and a spring tending to move said ring into position to permit said jaws to open.
9. In a machine of the character described, the combination of a frame, a member mounted thereon to move step by step and having an exhaust head and a valve for controlling the connection of said head to an exhaust pump, said head comprising a tubular boss, a tubular rubber stopper in said boss, means movable longitudinally of said head for compressing said stopper to constrict its bore and a rotatable cap on the lower end of said head for actuating by its rotation said stopper compressing means, and a rotatable key mounted in said frame to register with said head and to move vertically into engagement with said cap to rotate said cap while said member is stationary.
10. In a machine of the character described, the combination of a frame, a member mounted on said frame rotatably and provided with a plurality of exhaust heads and a valve for controlling the connection of said heads to an exhaust pump each head comprising a vertical tubular boss having therein a tubular rubber stopper, means for compressing said stopper to constrict its bore, and a rotatable cap on the bottom of each head for actuating said means to compress said stopper; driving means for rotating said member step by step to bring each head into working positions in succession, and two rotatable and vertically movable keys mounted on said frame at adjacent working positions to register with the caps on said exhaust heads in said positions, and means actuated by said driving means while said member is stationary for simultaneously raising said keys into engagement with the caps on the heads in registry therewith, turning said keys in opposite direction to compress the stopper in one head and to release the stopper in the adjacent head, simultaneously lowering said keys.
11. In a machine of the character described, the combination of a rotatable member having thereon an exhaust head and a valve for controlling the connection of said head to an exhaust pump, a tubular rubber stopper in said head for holding an exhaust tube in and connecting it air-tight to said head, means for fusing off the exhaust tube in said head, and means controlled by said valve for subsequently supplying air under pressure to said head to blow out the fused off end of the exhaust tube.
12. In a machine of the character described, the combination of a movable member, a bulb fork on said member, and an exhaust head on said member in alignment with said fork and comprising a tubular boss, a tubular rubber stopper in said boss, a vertically movable sleeve on said tubular boss having a flange on the upper end, and means actuated in synchronism with the movement of said member to automatically raise said sleeve along the exhaust tube in said head into position to surround the exhaust tube and adjacent leading-in wires and engage the stem of the mount to support it.
13. In a machine of the character described, the combination of an exhaust head comprising a fixed tubular boss, a tubular rubber stopper in said boss and a water jacketed sleeve movably telescoped on said boss to substantially enclose the upper part of said boss and its contained rubber stopper when said sleeve is lowered.
14. In a machine of the character described, the combination of a rotatable member having a plurality of work holders, each comprising an exhaust head and a cooperating bulb fork in alignment with said head, and a valve for automatically controlling the connection of said heads to an exhaust pump during the rotation of said member, driving means for rotating said member step by step, and means controlled by said driving means for automatically moving each bulb fork away from its cooperating exhaust head at the loading position and subsequently at a succeeding position lowering the bulb fork to bring the bulb into place over the mount held in the exhaust head.
15. In a machine of the character described, the combination of an intermittently rotatable member having an exhaust head and a bulb fork mounted in alignment with said head on a vertically reciprocating rod, driving mechanism for rotating said member, a reciprocating push rod mounted to align with said rod when said rotary member is stationary, a resilient catch for holding said lifter in either of two extreme positions, and push rod actuating means controlled by said driv-

- ing mechanism for moving said push rod into one extreme position when said bulb rod is in registry with it and thereby moving said bulb holder away from the exhaust head, and 5 for positively moving said push rod to the other extreme of its position in another position of said member to permit said bulb holder to return to its initial position, and thereby place the bulb over a mount in said 10 exhaust head.
16. In a machine of the character described, the combination of movable member having an exhaust head fixed thereon and a cooperating bulb fork mounted on said member to 15 move in alignment with said head, driving mechanism for moving said member intermittently to place said head in a plurality of working positions in succession, sealing-in burners mounted adjacent the path of each 20 exhaust head and bulb fork in position to seal a mount in said head into a bulb held in said bulb fork, auxiliary burners mounted adjacent said sealing-in burners and at a position further along the path of said sealed-in 25 bulb to keep plastic the joint between the stem and the bulb while the head is in said position, and means actuated by said driving mechanism to raise said bulb fork while said head is in said position and said joint is plastic 30 and move the bulb slightly away from the exhaust head and thereby stretch and work the plastic joint.
17. In a machine of the character described, the combination of a rotatable member having 35 thereon means for holding a mount and a bulb in proper relation, burners adjacent the path of said means to seal said mount into said bulb and simultaneously melt off the surplus portion of the neck of the bulb, and stationary members mounted adjacent 40 the path of the mount holder to form a passage in which the melted off portion of the bulb neck is broken when carried into it by the movement of said member.
18. In a machine of the character described, the combination of a rotatable member, means 45 on said member for holding a mount and a bulb in sealing-in relation, burners mounted adjacent the path of said member to seal said mount into said bulb, and leading-in wire fingers mounted adjacent the path of 50 movement of said member to bend back leading-in wires substantially parallel to the exhaust tube.
19. In a machine of the character described, the combination of a rotatable member, a 55 mount holder and a bulb holder on said member, sealing-in burners adjacent the path of said holders to seal the mount into a bulb, and double fingers mounted adjacent and 60 tangential to the path of said mount holder to oscillate into and out of operative relation to the exhaust tube, and to enter between the exhaust tube and leading-in wires parallel 65 thereto, said fingers being shaped to displace said leading-in wires away from the exhaust tube and toward the bulb.
20. In a machine of the character described, the combination of a movable member, mount holding means and a bulb holder carried on 70 said member, burners mounted adjacent the path of said member to seal the mount into a bulb, a sealing off burner mounted adjacent the path of said member to seal off the exhaust tube in said mount holder, a delivery 75 fork mounted adjacent the sealing off burner and having a resilient stop mounted to catch and bend back any leading-in wire parallel to the exhaust tube, and means for moving said delivery fork toward and away from the 80 exhaust tube in said holder.
21. In a machine of the character described, the combination of a rotatable member provided with exhaust heads, and a valve for controlling connections of said head to the preliminary vacuum pump, and to the final vacuum pump, of a valve responsive to the variation in pressure caused by a leaky lamp being connected through said valve to the preliminary vacuum pump, and means actuated 85 by said valve to automatically seal off the exhaust tube of the leaky pump.
22. In a machine of the character described, the combination of a rotatable member provided with exhaust heads and a valve for 90 controlling the connection of said head to a vacuum pump, of means responsive to leakage through one of said heads comprising a leak responsive valve comprising two chambers each containing a partition, a valve in 95 said partition, a flexible membrane dividing each chamber into two parts, the other part being connected to the vacuum pump and the inner parts connected to a gas supply, whereby a variation in pressure due to a leak 100 through one of said exhaust heads will move said membranes and thereby open the valve in said partition and permit gas to flow and a sealing off burner supplied from said inner parts and mounted in position to seal off the 105 defective exhaust tube.
23. In a device of the character described the combination of a rotatable member having fixed thereon an exhaust head for holding a 110 mount with a projecting exhaust tube and comprising a tubular rubber for gripping said exhaust tube to position the mount, and also to make an air-tight connection with said exhaust tube, a bulb holder on said member to suspend a bulb with its neck over a 115 mount held in said head, sealing-in burners mounted adjacent the path traversed by said exhaust head during the first part of its travel to seal the mount in said head into the neck of a bulb in said holder, and means responsive 120 to movement of said member for automatically exhausting the sealed in bulb through the bore of said head after it is beyond range of said sealing in burners and while it is traversing another part of its path.

24. In a combined sealing in and exhaust machine for incandescent lamps and similar devices the combination of sealing in burners, an exhaust pump, a tubular exhaust head for holding and making an air tight connection to the exhaust tube of the tubulated part of a lamp, a holder associated with said head to hold the untubulated part of the lamp in sealing in relation to the tubulated part in said head, and means for carrying said head and holder bodily into and out of range of said sealing in burners to seal said lamp parts together and then connecting said head to said exhaust pump.
- 15 25. In a combined sealing in and exhaust machine for incandescent lamps and similar devices a movable carrier, a tubular exhaust head on said carrier for holding and making an air tight connection to the exhaust tube of the tubulated part of a lamp, a holder associated on said carrier with said head to hold the untubulated part of the lamp in sealing in relation to the tubulated part in said head, sealing in burners adjacent one part of the path of said head, exhaust means controlled by said carrier, and actuating means for moving said carrier to carry said head into and out of range of said burners during one part of its travel and then to connect it to said exhaust means during a subsequent part of its travel.
- 20 26. A combined sealing in and exhaust machine for incandescent lamps and similar devices comprising a rotatable spider, a tubular exhaust head on said spider for holding and making an air tight connection to the exhaust tube of a tubulated mount, a bulb holder associated with said head to hold a bulb in
- 25 sealing in relation to the mount held in said head, sealing-in burners mounted adjacent the path of said head, an exhaust valve rotatable with said spider and having an exhaust port, actuating means for rotating said spider to carry said head into and out of range of said sealing in burners and then to connect it through said valve to said exhaust port.
- 30 27. In a machine of the character described for sealing in and exhausting a lamp having a mount with a projecting exhaust tube, the combination of an intermittently rotatable member having fixed on it an exhaust head comprising a tubular elastic holder for making an air tight connection to the exhaust tube of the mount, driving means for moving said member intermittently to place said head in a number of working positions in succession during its travel, a bulb holder on said member in alignment with said exhaust head, a sealing in burner rotatable about an axis in alignment with said exhaust head when said head is in a working position near the beginning of its travel and in a plane parallel to the plane of movement of said exhaust head for directing a flame upon said bulb to seal a mount held in said exhaust head into the bulb held in said bulb fork, a valve rotatable with said member and having a port communicating with the bore of said head, and a co-operating valve seat having an exhaust port which registers with said valve port when said head is in another and subsequent working position.
- 35 In witness whereof, I have hereunto set my hand this 21st day of September, 1925.

KARL MEY.

CERTIFICATE OF CORRECTION.

Patent No. 1,710,428.

Granted April 23, 1929, to

KARL MEY.

It is hereby certified that error appears in the printed specification of the above numbered patent requiring correction as follows: Page 9, line 92, claim 21, for the word "pump" read "lamp"; and that the said Letters Patent should be read with this correction therein that the same may conform to the record of the case in the Patent Office.

Signed and sealed this 11th day of June, A. D. 1929.

(Seal)

M. J. Moore,
Acting Commissioner of Patents.

24. In a combined sealing in and exhaust machine for incandescent lamps and similar devices the combination of sealing in burners, an exhaust pump, a tubular exhaust head for holding and making an air tight connection to the exhaust tube of the tubulated part of a lamp, a holder associated with said head to hold the untubulated part of the lamp in sealing in relation to the tubulated part in said head, and means for carrying said head and holder bodily into and out of range of said sealing in burners to seal said lamp parts together and then connecting said head to said exhaust pump.
- 15 25. In a combined sealing in and exhaust machine for incandescent lamps and similar devices a movable carrier, a tubular exhaust head on said carrier for holding and making an air tight connection to the exhaust tube of the tubulated part of a lamp, a holder associated on said carrier with said head to hold the untubulated part of the lamp in sealing in relation to the tubulated part in said head, sealing in burners adjacent one part of the path of said head, exhaust means controlled by said carrier, and actuating means for moving said carrier to carry said head into and out of range of said burners during one part of its travel and then to connect it to said exhaust means during a subsequent part of its travel.
- 20 26. A combined sealing in and exhaust machine for incandescent lamps and similar devices comprising a rotatable spider, a tubular exhaust head on said spider for holding and making an air tight connection to the exhaust tube of a tubulated mount, a bulb holder associated with said head to hold a bulb in
- 25 sealing in relation to the mount held in said head, sealing-in burners mounted adjacent the path of said head, an exhaust valve rotatable with said spider and having an exhaust port, actuating means for rotating said spider to carry said head into and out of range of said sealing in burners and then to connect it through said valve to said exhaust port.
- 30 27. In a machine of the character described for sealing in and exhausting a lamp having a mount with a projecting exhaust tube, the combination of an intermittently rotatable member having fixed on it an exhaust head comprising a tubular elastic holder for making an air tight connection to the exhaust tube of the mount, driving means for moving said member intermittently to place said head in a number of working positions in succession during its travel, a bulb holder on said member in alignment with said exhaust head, a sealing in burner rotatable about an axis in alignment with said exhaust head when said head is in a working position near the beginning of its travel and in a plane parallel to the plane of movement of said exhaust head for directing a flame upon said bulb to seal a mount held in said exhaust head into the bulb held in said bulb fork, a valve rotatable with said member and having a port communicating with the bore of said head, and a co-operating valve seat having an exhaust port which registers with said valve port when said head is in another and subsequent working position.
- 35 In witness whereof, I have hereunto set my hand this 21st day of September, 1925.
